UNITED STATES PATENT OFFICE.

ALBERT F. SCHROEDER, OF CLEVELAND, OHIO.

HOSE-CLAMP.

1,199,826.

Specification of Letters Patent.

Patented Oct. 3, 1916.

Application filed April 10, 1914. Serial No. 830,859.

To all whom it may concern:

Be it known that I, ALBERT F. SCHROEDER, a citizen of the United States, residing at Cleveland, in the county of Cuyahoga and State of Ohio, have invented a new and useful Improvement in Hose-Clamps, of which the following is a specification, the principle of the invention being herein explained and the best mode in which I have contemplated applying that principle, so as to distinguish it from other inventions.

My invention constitutes an improvement in hose-clamps whereby the construction of the clamp itself and hence the binding action between it and the members which it is desired to secure to each other may be effected with absolute uniformity. Accordingly, the advantage derived consists in imparting the same progressive pressure at all points around the parts which are actually inclosed by the clamp, and in consequence leakage is more likely precluded.

To contrive an article which shall be simple and hence economical of manufacture has been held in mind as one object.

A further object of my preferred form has been to make possible the adaptation of certain parts for utilization in all the various sizes of clamps required.

My inventive conception is associated with means which are hereinafter explained and variously combined in the claims. While the annexed drawing and particular description thereof, jointly set forth in detail preferred and modified forms embodying my invention, it should be understood that the means only exemplify some of many diversified mechanical forms with which the principle of my invention may be justly applied.

Adverting to the drawing: Figure I is an end view of a hose-clamp embodying my invention in its open or expanded position around two other parts. Fig. II is a similar view showing the clamp after being tightened. Fig. III is a side view of the clamp itself. Fig. IV is a top plan view of Fig. III. Fig. V is a perspective view of one detail. Fig. VI is a side view of another detail as manufactured. Fig. VII is a side view of a second modification. Fig. VIII is an end view of Fig. IX.

The use to which my invention is ordinarily put is to fasten together, say, a hose and a pipe length. These I have designated in the several views where shown, as H and P respectively. The practical application of

my invention is to envelop that portion of the hose length which incloses a certain portion of the pipe and thereafter to effect the constriction of the clamp to exert a binding of the hose against the pipe, to the end of avoiding leakage at the point of connection therebetween.

My construction involves a flexible band A preferably of spring metal. This band has its ends curved in opposed directions to form hooked extremities a' which extend toward each other. This band is separately shown in Fig. VI and as will be apparent, may be manufactured in various lengths from stock of given dimensions. My conception is not to have the band A as the primary portion only partly surround the hose and pipe, but to entirely surround these parts to be fastened and then continue nearly once again around the same. In other words, I purposely convolve the band upon itself to form one complete convolution and the major portion of another as perhaps best seen in Fig. III. As so formed the two hook portions a' will each lie to one side for convenience, usually the upper side of the median horizontal plane of the pipe.

My invention furthermore involves the provision of a pair of clips B. Each of these clips B has a lower portion b' of arcuate contour, a lower extremity b² provided with a transversely elongated aperture b³, and finally with an upper extremity b⁴ which is flanged upwardly and provided with a circular opening b⁵. These clips are preferably of metal of sufficient thickness to be rigid. The apertures b³ are each designed to accommodate one of the flat hooks a' such that when the clips B are assembled with respect to the band A the partial convolution of the latter is more nearly completed.

A bolt C is adapted to extend through the two openings b⁵ and the provision of the usual nut c' makes possible the drawing together of the flanges b⁴, as will be readily understood. In this manner, my hose-clamp as an entirety may be constricted in a manner common to the art.

As contradistinguished from other articles of this character with which my experience has made me aware, my invention involves what is in effect a simultaneous and uniform constriction of the two convolutions. By reason of this circumstance each convolution and particularly the upper arcuate portion of that convolution which is

entirely formed by the band A, is caused to move inwardly in a radial direction. This resultant movement in turn positively insures against a puckering or wrinkling of the hose upon the pipe and therefore insures a flat or uniform contiguity between the hose and pipe, and obviously this is the only absolute guarantee against leakage.

- 10 Figs. VII and VIII illustrate a modification. The band a^4 utilizes a piece of wire having downwardly extending hooked extremities a^5 , and these are adapted to extend through circular apertures a^6 in the lower extremities of a pair of clips b^6 .
15 These clips b^6 are provided on each side with stiffening flanges b^7 , have their free extremities b^8 bent upwardly and provided with openings b^9 through which the bolt C is intended to project.
20 My invention being thus described with sufficient thoroughness, what I desire to secure by Letters Patent and therefore claim specifically, is:

- 25 1. A hose clamp comprising a smooth flexible band having its opposite ends bent to form hook portions projecting in the same direction, said band being helically convolved one and a half times to present said hook portions projecting outwardly, and a pair of similarly smooth and partially arc-

uate clips having openings at corresponding ends and loosely engaged therethrough by said hooks, each of said clips being furthermore fashioned with an outward projection each likewise provided with an opening, and adjustable means for drawing said projections together in an arcuate direction, the arrangement being such that an equal constriction effect is exercised in both directions around the clamp and smoothly between said clips.

2. A hose clamp comprising a plain flexible band having each of its two ends bent at an angle with respect to the longitudinal extent of said band to form hooks, said band being adapted to be convolved upon itself, and a pair of arcuate clips loosely connected with such hooks of the band respectively and adapted to complete a second convolution, and means for drawing said clips together whereby a uniform constriction of the whole may be effected therearound without presenting meeting edges for movement past each other in the plane of the proximate portion of said hose.

Signed by me, this 1st day of April, 1914.

ALBERT F. SCHROEDER.
